UNITED STATES PATENT OFFICE.

HENRY BURRMANN, OF DAVENPORT, IOWA.

RAILWAY-CAR TRUCK.

1,237,166.

Specification of Letters Patent. Patented Aug. 14, 1917.

Application filed December 15, 1916. Serial No. 137,109.

To all whom it may concern:

Be it known that I, HENRY BURRMANN, a citizen of the United States of America, and a resident of Davenport, county of Scott, 5 State of Iowa, have invented certain new and useful Improvements in Railway-Car Trucks, of which the following is a full and clear specification.

In the railway cars now in common use, the 10 car-body-bolster rests rigidly on the truck-bolster and the ends of the truck-bolster are slidably engaged in vertical slots in the truck side frames, springs being arranged in the side frames to give the necessary resiliency and tie bars or other devices being arranged to connect the truck side frames. In this construction, the lateral thrusts due to the tendency of the car body to move laterally on the trucks are transmitted directly 20 to the side frames of the truck, thereby necessitating the employment of heavy side frames and also the tie bars or other connections above referred to. It is the main object of my present invention to relieve the 25 side frames of the truck greatly from these heavy thrusts, so as to thereby make it possible to not only do away with the tie bars but also to reduce the weight of the side frames, as more fully hereinafter set forth.

30 A further object of this invention is to provide the truck with side bearings which will automatically adjust themselves to the proper height in accordance with the load carried by the car and which also will cushion the thrusts of the car body when it tilts and tend to stabilize it, as more fully hereinafter set forth.

In the drawings—

Figure 1 is a plan view of one side of a 40 truck constructed in accordance with my invention;

Fig. 2 is a view of bolster partly in side elevation and partly in vertical section;

Fig. 3 is a broken-away perspective view 45 of a portion of the truck-bolster body;

Figs. 4, 5, 6, 7, 8 and 9 are detail views hereinafter described.

Referring to the drawings annexed by reference characters, *a* designates a body bolster 50 having secured to it a center plate having an annular bearing *b* which fits in an annular bearing channel in the center bearing *c* mounted on the truck bolster. The center plate of the car bolster is provided 55 with a pair of arcuate lateral bearing plates *d* at its opposite sides, which are supported on a series of anti-friction rollers *e* mount-

ed in arcuate race-ways formed in the upper surface of the center bearing *c* outside of and concentric with the usual annular bearing therein. These supplemental outside bearings serve not only to reduce friction while the car is traveling on a curve, but also tend to prevent the car from tilting. It will be observed that the anti-friction rollers *e* are readily arranged, so that each roller will have no more than a line contact against the raceway surfaces, thus reducing the friction to a minimum in these supplemental bearings.

The center bearing *c* is centered by the usual king bolt *f* which extends down through the bolster *a* and the two center bearing members and has its lower ends stepped in a recess *g* formed in the bottom of a pocket, this pocket being open at its upper side and being formed by the side walls of the truck bolster and transverse partition walls *h*, the bottom *i* of this pocket lying preferably at a point above the bottom side 80 of the bolster.

The center bearing *c* of the truck bolster is supported entirely by a plurality of springs *j* inclosed within the pocket or well and resting on the bottom thereof, the center bearing being prevented from turning and being guided in its vertical movements by a pair of depending walls or flanges *k* which slidably engage the outer faces of the guide walls *h* in the bolster. With this 90 construction it will be observed that any number and arrangement of coil springs may be arranged in the pocket.

The ends of the truck bolster are rigidly connected in any suitable way with the side 95 frames *l* of the truck; I prefer making this rigid connection by means of a notch *m* on the upper side of the side frame, the end of the bolster being adapted to fit this notch closely and to be placed therein from the top 100 of the side frame. The bolster rests rigidly upon the bottom of the notch in the side frame, the under side of the bolster being provided with transverse flanges *n* which engage the opposite sides of the frame and prevent all lateral movement of the bolster on the frame. With my resilient center bearing, it will be observed that the thrust, due to the tendency of the car body to move sidewise while running, will be largely taken 110 up by flanges *k* of the center plate and the guide walls of the bolster *h*, thus relieving the side frames materially from side thrusts, thereby enabling me not only to make the

side frames lighter in weight, but also to do away with the usual tie rod between the side frames.

In suitable pockets formed in the top surface of the truck bolster are mounted the side bearing blocks *o* whose lower ends are approximately wedge-shaped, to adapt them to fit against the correspondingly inclined adjacent faces of thrust blocks *p* inclosed 5 within the bolster and adapted to slide along a bearing *q* inclining downwardly and inwardly toward the center of the bolster. Integrally formed on the inner face of each of the thrust blocks is a pair of ears *r* adapted 10 to receive between them the longitudinally slotted end of the link *s* whose inner end is connected to the adjacent wall *k* of the center bearing, the connection consisting of the pivot *t* whose axis is horizontally transverse 15 with respect to the bolster and whose ends are supported in suitable flanges formed on said flange *k*. The outer end of the link is connected pivotally to the said ears *r* by a transverse pivot *u*, this pivot extending 20 through a slot in the link and thus permitting a limited amount of lost motion between the thrust block and the link. Mounted pivotally on the pin *u* is a cap *v* which 25 embraces the outer end of a coil spring *w* which surrounds the link *s* and has its inner end pressing, through the medium of a rub plate *x*, against the adjacent face of the transverse wall *y* formed in the bolster.

The adjacent faces of the block *p* and the 30 cap *v* are in contact so that the thrust will be transmitted to the spring through the cap, and, in order that this block and cap shall have a pivotal action relatively to each other, one of the parts is concaved and 35 the other convexed to form in effect a ball-and-socket joint.

Spring *w* being under tension, the cap *v* is pressed outwardly until the pin *u* rests in the outer end of the slot in the link. 40 The load on the center plate causes the inner end of the spring *w* to move downwardly, the rub plate *x* sliding down on the outer face of the wall *y*. This action results in drawing the thrust block *p* downwardly on its inclined support and thus positions it properly for the particular load the car is carrying. When the car body tilts in rounding a curve or when overloaded on one side, pressure on the side bearing block *o* forces 45 the same downwardly and thus cams or wedges the thrust block inwardly, its movement being reacted by spring *w*. The slot in which pin *u* slides is large enough to prevent putting rod *s* in compression in 50 case an overload on block *o* should push block *p* to its limit inwardly. It will thus be observed that my improved side bearing devices not only cushion the tilting move-

ment of the car body, but also tend strongly to stabilize it against rocking movements. 65

It will be understood, of course, that with this type of truck, the axles are journaled in the usual journal boxes which are either fastened in the usual rigid way to the ends of the truck side frames or cast integral, so 70 that the relative positions of the axles and the truck bolster will always be maintained. In this way, the two axles and the two side frames and the truck bolster form in effect a rigid truck. This enables me to support 75 the brake hangers upon the truck bolster, where they will always maintain their proper relative positions with respect to the wheels. For this purpose, I mount the brake hanger brackets *a'* upon the opposite 80 sides of the truck bolster. I prefer casting the truck bolster in a single piece, as shown, but it will be understood that it may be made in other ways without departing from the spirit of my invention. When the truck 85 bolster is thus made of a casting, the brake hanger brackets *a'* will be cast integral therewith.

The nature and scope of the invention having been thus indicated and its preferred embodiment having been specifically described, what is claimed as new is:

1. A side bearing arrangement for trucks, consisting of vertically movable side-bearing-blocks, thrust blocks in the bolster 95 against which the side-bearing-blocks normally bear, and means operated by the load for positioning said thrust blocks, said means embodying a resiliently supported center bearing for the car body and also 100 resilient means interposed between the center bearing and said thrust blocks.

2. In a car truck, a pair of side frames, each having a suitable notch in its top side, a bolster whose ends snugly rest in said 105 notches, depending projections on the bolster being provided for preventing endwise movement of the bolster with respect to the side frames, said projections engaging the opposite faces of the side frame along the 110 bottom of the notch, a center bearing plate for supporting the car body and resilient means for supporting the center bearing plate in the bolster, said bolster being provided with a pocket for the reception of 115 said resilient means and said center bearing plate being provided with depending flanges guided vertically by contact with portions of the bolster, these flanges serving to prevent the center plate from rotating and also 120 from any lateral movement independent of the bolster.

In testimony whereof I hereunto affix my signature.

HENRY BURRMANN.
